Primary Examiner — Philip S Hyder*Assistant Examiner* — Darlington Ly(74) *Attorney, Agent, or Firm* — Norton Rose Fulbright
Canada LLP(57) **CLAIM**

The ornamental design for an electric bicycle, as shown and described.

DESCRIPTION

FIG. 1 is a right rear perspective view of an electric bicycle in accordance with our new design.

FIG. 2 is a left front perspective view of the design of FIG. 1.

FIG. 3 is a top plan view of the design of FIG. 1.

FIG. 4 is a front elevational view of the design of FIG. 1.

FIG. 5 is a rear elevational view of the design of FIG. 1.

FIG. 6 is a left side elevational view of the design of FIG. 1; and,

FIG. 7 is a right side elevational view of the design of FIG. 1. The broken lines shown in the drawings illustrate portions of the electric bicycle that forms no part of claimed design.
